UNITED STATES PATENT OFFICE.

DANIEL EMIL ERICKSON, OF LONDON, ENGLAND.

FURNACE.

Application filed May 31, 1922. Serial No. 564,925.

To all whom it may concern:

Be it known that I, DANIEL EMIL ERICKSON, a citizen of the United States of America, residing at London, England, have invented a new and useful Improvement Relating to Furnaces, of which the following is a specification.

This invention relates to furnaces and has particular reference to the means employed 10 in boiler furnaces for burning oil fuel and for rendering them capable of conversion from coal burning to oil burning furnaces and vice versa as desired.

In order to provide the necessary air admission space and permit of mounting the 15 oil burner centrally in the front of the furnace box or combustion chamber it is usual to employ furnace fronts specially designed for the purpose although segmentally assembled 20 annular baffle plates or diaphragms have been employed. The chief object of the present invention is to provide an improved annular baffle plate or diaphragm capable of being fixed in position in and 25 removed without difficulty from furnaces of slightly different diameter without necessitating any special design of the front portion of the furnace or requiring any alteration 30 of the ordinary designs, whilst ensuring a rigid airtight mounting of the baffle plate or diaphragm in the furnace proper notwithstanding slight irregularities or variations in diameter and without precluding 35 the possibility of expansion and contraction.

According to the present invention the baffle plate or diaphragm comprises an annular assembly of plates adapted to co-operate with means whereby relative angular 40 movement between them causes the segments to automatically spread radially outwards thus causing their outside edges to engage more firmly on the seating or wall against which they bear. According to one construction 45 this automatic spreading motion of the segments may conveniently be obtained by a cam action between the outer curved surface of a lining ring and the inner curved surface of the central aperture in the 50 assembly of segments so that an angular adjustment of the lining ring causes all the segments to spread equally. In order that the radially outward pressure may be uniformly distributed each segment may have 55 two or more spaced cam surfaces on its inner periphery, a corresponding number of

cam surfaces or projections being of course formed on the lining ring. The lining ring may itself be formed segmentally and of considerable width so as to constitute strictly 60 speaking an inner supplementary plate or assembly of segmental plates, and the cam action may be obtained by cam surfaces or projections formed actually on the edges of the plates or by similarly acting angularly 65 movable means interposed between the two assemblies. In the preferred construction the aforesaid interposed means are constituted by the bolts employed to clamp together edge or cover plates provided adjacent 70 the opposed edges of the main or outer assembly of diaphragm segments and the inner supplementary assembly.

In order to ensure a firm airtight seating or bearing between the outer edge or peripheral surface of the diaphragm and the internal surface of the furnace against which it is pressed I may interpose a packing of yieldable material such as asbestos, this material being held compressed in the 80 annular space between the opposing surfaces, and in order to improve the effectiveness of the joint formed by this packing and to ensure that it will remain in the best possible position I may shape the outer periphery of the segments to retain the packing in position. For this purpose I may form the said periphery with a groove or 85 with a laterally offset flange forming a channel, the said groove or channel serving 90 to partly house the packing.

The above described radially expansible furnace diaphragm is particularly applicable to boilers in which the furnace box has a corrugated cylindrical wall as it can 95 readily be fixed in position between two of the forwardly disposed corrugations and readily removed therefrom, but it is obviously applicable to other forms of furnace as for example Lancashire boilers.

The invention will now be described more fully with reference to the accompanying drawings which illustrate several practical embodiments of the invention.

Figure 1 is an axial sectional elevation 105 of the front part of a furnace equipped with an ordinary Howden draft type of front and one of my improved baffle plates or diaphragms, and

Figure 2 is a fragmentary face view of a 110 portion thereof.

Figure 3 is an axial sectional elevation of

the front part of a furnace equipped with an ordinary Howden draft type of front and another constructional form of my improved diaphragm.

5 Figure 4 is a fragmentary face view of a portion of the diaphragm shown in Figure 3.

Figure 5 is a face view,

Figure 6 a sectional view and

10 Figure 7 an enlarged detail view of a further modified construction of the diaphragm.

In the drawings the furnace wall is indicated by the reference numeral 1 the annular diaphragm segments by 2 and the lining ring by 3.

20 Referring first to the construction shown in Figures 1 and 2 it is seen that the inner periphery of the annular diaphragm is formed with cam surfaces 4 and the outer periphery of the lining ring with co-operating cam surfaces 5 in a peripheral groove 6. The annular diaphragm is composed of segments having radial abutting flanges connected together by bolts passing through 25 radially elongated slots in the flanges. It will therefore be understood that angular movement of the ring 3 will cause the segments of the diaphragm 2 to spread outwards and become firmly seated at their outer periphery against the furnace wall 1. In order to ensure an airtight joint, packing 7 in a seating 8 near the outer periphery of the diaphragm is interposed between the 30 abutting surfaces. In Figure 1 the entire diaphragm is shown seated in a corrugation in the wall of a corrugated furnace but obviously it can be fitted in a straight portion of the wall or in a plain cylindrical furnace.

35 40 It will be understood that the lining ring may be segmental and of considerable width so as to constitute a substantial part of the surface of the entire diaphragm in which case it may be more accurately termed an inner supplementary assembly of segments as before mentioned. Moreover the cam surfaces 4 and 5 need not both be extensive as shown in Figures 1 and 2 but either of them might be reduced to the size of mere 45 projections. The function of such projections may be satisfactorily performed by bolts securing edge plates together and to the adjacent edges of the diaphragm segments 2 and supplementary segments 3 as 50 shown in Figures 3 and 4 and Figures 5 to 7, which will now be described.

55 Referring now more particularly to Figures 3 and 4 it is seen that I have provided segmental edge plates 9 secured together by 60 bolts 10, the said plates forming grooves 6 into which the adjacent edges of the segments 2 and 3 fit whilst the bolts 10 serve the double purpose of securing the plates 9 and segments 2 and 3 together and operating as projections to coact with the cam sur-

faces 4. It will be understood that if the segments 2 are slack an angular adjustment of the edge plates and bolts 10 will cause the bolts to press upon the cam surfaces 4 and thereby spread the segments into close 70 contact against the furnace wall.

75 Mounted on the ring 3 by hinges 11 I have shown a door 12 having a central aperture in which is fitted the inwardly converging air delivery ring 13. It is to be noted that this ring through which entering air is delivered to the interior of the furnace is not U-shaped in cross section or flared inwardly and outwardly as is customary but is substantially straight in cross 80 section and directed towards the furnace at such an angle to the conical flame from the burner that the area 14 exposed to intense heating unrelieved by the sweeping of entering air over it is a minimum.

85 My improved furnace diaphragm is applicable either to forced draft or to natural draft furnaces. For the purpose of illustration I have shown the diaphragm in Figures 1 and 3 as employed in conjunction 90 with the usual frame and front fire doors of a furnace front of the Howden type. I have shown mounted centrally in this front an oil burner tube and tip 15 surrounded by a tubular barrel 16 on which is mounted 95 a flame cone 17 and main air deflector 18 all substantially as described in my prior British Patent No. 163273.

100 It is to be observed that the segments 2 are shown provided with broad feet 19, each segment having one or more such feet to strengthen it and facilitate its positioning during assembly.

105 In the constructional arrangement shown in Figures 5, 6 and 7 the entire furnace diaphragm comprises seventeen separable plates namely, four cam-edged segments 2, three supplementary segments 3, four back and four front broken-jointed edge plate segments 9, the vertically hinged door 12 110 (having a circular aperture to which may be fixed the conical air delivery ring 13) and the cover plate 20 on the lower part of the door frame.

115 In order to facilitate the travel of the bolts 10 over the cam surfaces 4 each bolt may be provided with a short sleeve or loose ring 21 to minimize friction as shown clearly in Figure 7.

120 The cover plate 20 is normally held in position by two catches 22. When this plate is removed the door 12 may be swung open about its vertical hinge, thereby providing a conveniently large opening for entry of an engineer into the furnace.

125 It is seen in Figure 3 and also in Figures 4 and 5 that an annular flange or ledge is formed near the periphery of the segments 2 for the purpose of seating a ring of packing 7 which prevents leakage of air past 130

the diaphragm at its periphery. The edge plates 9 prevent leakage between the adjacent curved edges of the segments 2 and 3.

5 In assembling the entire diaphragm as shown in Figures 3 or 5, the diaphragm segments 2 are put in position, then the edge plates 9 are assembled and bolted together and are given an angular turn to spread the 10 segments 2, then the nuts are slackened to slightly open the space between the edge plates, then the supplementary segments 3 are fitted by dropping their edges into the groove between the edge plates and then 15 the bolts are tightened up again.

What I claim and desire to secure by Letters Patent of the United States is:—

1. A furnace diaphragm, comprising an annular assembly of segmental plates, and 20 means co-operating with said assembly whereby relative angular movement between them causes said plates to spread radially outwards into close contact with the furnace wall.

25 2. A furnace diaphragm comprising an annular assembly of segmental plates and angularly adjustable means co-operating with the internal periphery of said assembly to spread the segments thereof radially outwards.

3. A furnace diaphragm comprising an annular assembly of segmental plates, and means whereby a spreading effect is produced upon the segments of said assembly 35 by a cam action thereon during relative angular adjustment between said means and said assembly.

4. A furnace diaphragm comprising an annular assembly of segmental plates, a lining ring to said assembly, and means where- 40 by an angular adjustment relatively to said assembly produces a radially spreading effect on the segments thereof.

5. A furnace diaphragm comprising an annular assembly of segmental plates, a segmental lining ring, and means whereby an angular adjustment relatively to said assembly produces a radially spreading effect on the segments thereof.

50 6. A furnace diaphragm comprising an annular assembly of segmental plates, an inner supplementary plate, an annular edge plate covering the adjacent peripheries of said assembly and plate, and means interposed between said peripheries to hold said edge plate in position and serving by angular adjustment relatively to the assembly to spread the segments thereof radially outwards.

60 7. A furnace diaphragm comprising an annular assembly of segmental plates, an inner supplementary plate, annular edge plates covering the adjacent peripheries of said assembly and plate, and means inter- 65 posed between said peripheries to hold said

edge plates in position and serving by angular adjustment relatively to the assembly to spread the segments thereof radially outwards.

8. A furnace diaphragm comprising an annular assembly of segmental plates, an inner supplementary assembly of segments, inner and outer annular edge plates covering the adjacent peripheries of the two assemblies, bolts passing between said assemblies and holding the edge plates in position, and cam acting surfaces on the inner periphery of the outer assembly for co-operation with said bolts whereby angular movement of said bolts and edge plates effects a radial spreading of the segments of the outer assembly.

9. A furnace diaphragm comprising an annular assembly of segmental plates, an inner supplementary assembly of segments, inner and outer annular edge plates covering the adjacent peripheries of the two assemblies, bolts passing between said assemblies and holding the edge plates in position, anti-friction sleeves on said bolts, and cam acting surfaces on the inner periphery of the outer assembly for co-operation with said bolts whereby angular movement of said bolts and edge plates effects a radial spreading of the segments of the outer assembly.

10. A furnace diaphragm comprising an annular assembly of segmental plates, means co-operating with said assembly whereby relative angular movement between them causes said plates to spread radially outwards into close contact with the furnace walls, and means on said assembly adjacent its outer periphery to provide a seating for packing material between the assembly and the furnace wall.

11. A furnace diaphragm comprising an annular assembly of segmental plates, means co-operating with said assembly whereby relative angular movement between them causes said plates to spread radially outwards into close contact with the furnace walls, and a circular lateral flange adjacent the outer periphery of said assembly to retain packing material between the assembly and the furnace wall.

12. A furnace diaphragm comprising an annular assembly of segmental plates, an inner supplementary plate, annular edge plates covering the adjacent peripheries of said assembly and plate, means interposed between said peripheries to hold said edge plates in position and serving by angular adjustment relatively to the assembly to spread the segments thereof radially outwards, and a door attached to said inner plate.

13. A furnace diaphragm comprising an annular assembly of segmental plates, an inner supplementary plate, annular edge plates covering the adjacent peripheries of

said assembly and plate, means interposed between said peripheries to hold said edge plates in position and serving by angular adjustment relatively to the assembly to spread the segments thereof radially outwards, and a door mounted on vertical hinges on said inner plate.

14. A furnace diaphragm comprising an annular assembly of segmental plates, an inner supplementary plate, annular edge plates covering the adjacent peripheries of said assembly and plate, means interposed between said peripheries to hold said edge plates in position and serving by angular adjustment relatively to the assembly to spread the segments thereof radially outwards, and an air deflector mounted in a central opening of the inner plate.

15. A furnace diaphragm comprising an annular assembly of segmental plates, an inner supplementary plate, annular edge plates covering the adjacent peripheries of said assembly and plate, means interposed between said peripheries to hold said edge plates in position and serving by angular adjustment relatively to the assembly to spread the segments thereof radially outwards, and an inwardly converging air deflector mounted in a central opening of the inner plate and formed substantially straight in cross section.

16. A furnace diaphragm comprising an annular assembly of segmental plates, an inner supplementary plate, annular edge plates covering the adjacent peripheries of said assembly and plate, means interposed

between said peripheries to hold said edge plates in position and serving by angular adjustment relatively to the assembly to spread the segments thereof radially outwards, a door attached to said inner plate, and an air deflector mounted in a central opening in said door.

17. A furnace diaphragm comprising an annular assembly of segmental plates, an inner supplementary plate, annular edge plates covering the adjacent peripheries of said assembly and plates, means interposed between said peripheries to hold said edge plates in position and serving by angular adjustment relatively to the assembly to spread the segments thereof radially outwards, a door hinged on said inner plate, and an inwardly converging air deflector mounted in a central opening in said door.

18. A furnace diaphragm comprising an annular assembly of segmental plates, an inner supplementary assembly of segments, annular edge plates covering the adjacent peripheries of said assemblies, bolts passing between said peripheries to hold said edge plates in position, cam surfaces on the inner periphery of the main assembly to co-operate with said bolts and cause a radial spreading of the segments of the assembly when the bolts and edge plates are angularly adjusted, a door vertically hinged on said inner assembly, an inwardly directed conical air deflector mounted in a central opening in said door, and a cover plate detachably mounted beneath said door.

DANIEL EMIL ERICKSON.
